[57] CLAIM

The ornamental design for combined wall-mounted cabinet and console for business and home planning organization systems, as shown and described.

DESCRIPTION

FIG. 1 is a front perspective view of a combined wall-mounted cabinet and console for business and home planning organization systems showing my new design; FIG. 2 is a rear perspective view thereof;

FIG. 3 is an enlarged front elevational view thereof, with the cabinet doors shown in a closed position;

FIG. 4 is a right side elevational view thereof, the left side being a mirror image of that shown and with the cabinet doors shown in a closed position;

FIG. 5 is a top plan view thereof, the bottom being a mirror image of that shown, and with the cabinet doors shown in a closed position; and

FIG. 6 is a vertical cross-sectional view thereof, taken along line 6—6 of FIG. 1, but with the cabinet doors shown in a closed position.
